UNITED STATES PATENT OFFICE.

MILES E. BAILEY, OF WASHINGTON, DISTRICT OF COLUMBIA.

ELEVATING-TRUCK.

1,146,779.

Specification of Letters Patent.

Patented July 20, 1915.

Application filed November 29, 1913. Serial No. 803,645.

To all whom it may concern:

Be it known that I, MILES E. BAILEY, a citizen of the United States of America, residing at Washington, District of Columbia, have invented certain new and useful Improvements in Elevating-Trucks, of which the following is a specification.

This invention relates to improvement in elevating trucks, and its main object is to design a simple and inexpensive truck adapted to move articles of furniture, heavy filing cabinets, stoves, bookcases, bureaus, chiffonniers, desks, automobiles, lathe machinery, and any other articles which stand on legs or wheels of sufficient height to enable the truck to be run under, or articles which may be placed on a base, raised platform, or box, with legs, such as paper, parts of machinery in course of construction, chips from lathes, etc.

It is also my purpose to provide a new and improved lever mechanism for operating all kinds of lifting jacks and elevating devices.

Other special features of my invention will be pointed out hereinafter.

One embodiment of my invention is shown in the accompanying drawing wherein—

Figure 1 is a plan view of a complete truck constructed in accordance with this invention. Fig. 2 is an end elevation of the same. Fig. 3 is a sectional detail view on an enlarged scale of one of the corner posts showing how it is attached to the frame. Fig. 4 is a fragmentary sectional view of the retaining hook showing a slightly modified form. Fig. 5 is a fragmentary perspective view of a modified form of one of the secondary levers.

Similar reference characters designate like parts throughout the several views.

The truck comprises essentially a suitable base frame, a movable platform and an elevating mechanism connecting said base and platform. The whole leverage system by which the platform is raised and lowered is constructed according to this invention so as to give the maximum leverage with a minimum of parts, and so as to occupy the minimum space in a vertical direction. Only two sets of levers are used, the first set comprising a single lever of the second class, which I term the actuating lever, and the second set comprising a plurality of levers, preferably of the first class, each of which is connected as near the same point on the ac-

tuating lever as the mechanical construction will permit. These levers, which I term secondary levers, extend in fan-like or radial formation from these adjacent points of connection to the actuating lever to separated points on the platform, preferably to the corners, so that the lifting force on the platform is distributed where most needed, while the actuating force need only be applied at one point on the actuating lever. The specific construction of these parts is preferably as follows:

The truck as shown comprises a main base frame made up of angle bars 1 on the rear and two sides. The angle bars are joined at the front by a bent plate 2, thus completing the four sides of the frame. The frame is mounted on suitable rollers 3 so that the truck may be readily moved in any direction. Across the back is also secured a flat plate 4 to which are secured two plates having upstanding ears 5 which form a bearing 6 for the rear of the actuating lever 7. Said actuating lever is designed to be operated by a downward pressure of the foot and is provided on its outer end with a foot pedal 8 which may be formed by twisting said bar. A hook 9 is secured to the depressed portion 2' of plate 2 and is designed to catch over the lever 7 when the lever is in the down-most position and the movable frame or platform is in the uppermost position. Preferably, said lever 7 assumes a substantially horizontal position so that a maximum leverage may be obtained by the foot. As shown in Fig. 2, the pivot end is slightly higher than the pedal end 8, since end 8 is engaged under hook 9 but it will be apparent that when the lever is released, the descent of the platform will raise end 8, through the connections hereinafter described, above said pivot 5. The pivot 6 is made sufficiently loose so that sufficient lateral swing may be given the lever 7 so as to engage it with and disengage it from the hook 9.

The secondary levers 10 are pivotally secured to an intermediate portion of bar 7 by means of links 11. Each of said levers 10 in the preferred form of construction comprises two flat bars 12 and 13. These bars straddle each of the connections by means of which said levers are connected to other parts of the mechanism. Each link 11 is made from a single flat strip twisted so as

to lie flat against lever 7 and also so as to lie flat between bars 12 and 13. Both sets of joints by means of which the links are connected to the various levers are pivotal, so that upon swinging the actuating lever upon its hinge 6, the inner ends of the secondary levers 10 will be moved freely up and down. Said secondary levers are pivoted to the base-frame by means of uprights 14 having flattened heads 15. Said uprights or bolts extend through holes in the main frame. Pivot pins 16 extend through both bars of the levers and through holes in the flattened head 15. The levers 10 are pivotally secured to the platform 18 by being pivoted to depending posts 17 which may or may not be a part of the platform. I have shown the posts as being formed of separate bars secured to the platform in any approved manner such as by providing the end posts with a horizontal portion 18' and bolting or otherwise securing the angle iron 19 which makes up the greater part of the top frame to said horizontal portion 18' as is shown in Fig. 3. The lower portion of the post 17 may be made cylindrical as is shown at 20, and is vertically movable in a hole 21 provided in the base 1. Across the front of the platform 30 is provided an angle iron 22 which is secured to the main angle iron 19. The upstanding portion 23 of said angle iron 22 serves as a stop to limit the movement of the truck as it is thrust under the object to be raised. 35 Stops 24 are also provided on the angle iron 1 forming the base which are adapted to abut against the legs of the base of the article to be moved.

In the embodiment of the invention illustrated stops 24 are positioned to the rear of stop 23 so that the truck may be used with articles, the legs of which extend out beyond the main body. The truck is provided with a bail shaped handle 25 pivotally attached to the top frame. As shown in Fig. 1, the handle is in the folded position so as to be out of the way, while in Fig. 2 it is shown as partially raised. It is readily apparent that it may be used to both push and pull the truck.

A particular feature of the invention lies in the special form of pivots 14 which support the levers 10. It will be noted that these pivots are in the form of bolts supported on the frame by means of nuts 26. It is possible to adjust the height to which the platform may be raised or lowered by simply turning the nuts 26, which will raise or lower the bolts 14. This feature is of great importance, as it gives the truck a greater range of adjustment and adapts its use to many different kinds of articles. The height of the platform may be so adjusted that the platform will barely slide under the base of a case or file cabinet, so that no

lost motion of the actuating lever need take place. Any form of locking means for nuts 26 may be provided, such as nuts 27.

In Fig. 4 is shown a modified form of hook 9' which is provided with a plurality of teeth 28, so that the platform may be raised to different heights as required. In this modified construction the teeth are shown as beveled so as to grip more firmly the actuating lever 7. The hooks 9 or 9' 75 may be secured in place by a nut 29.

Fig. 5 shows a modified form of secondary lever 10' which is made of a single bar. When such a bar is used the bolts 14 may be provided with a divided head 15', which extends on each side of said bar and is pivotally secured thereto by means of a rivet or bolt 30.

The movable frame or platform may be connected to the fixed frame by means of spiral extension springs 31 which act to draw the movable frame quickly into the lowered position when the lever is released from hook 9, so that the truck may be readily withdrawn from beneath an object after moving it to the desired position.

The operation of the truck will be readily apparent from the foregoing description.

The platform is shown in Fig. 2 as raised with the lever secured under the hook. Upon release of the lever the platform will be immediately drawn down by gravity and by the springs 31, and the lever thrown up. By pressing one's foot on pedal 8 the lever 7 is swung downwardly, thus swinging the outer ends of levers 10 down, and elevating the platform. It is readily apparent that with my system of levers heavy loads may be raised with slight effort, a single man being able to move the heaviest filing cabinets unaided.

My invention is obviously capable of embodiment in many different forms, and I do not limit myself unnecessarily to any of the details of construction as herein described, as it is apparent that many modifications may be made within the scope of the following claims.

I claim:

1. In an elevating truck, a base and a movable platform, actuating means therefor, comprising a substantially horizontal actuating lever pivoted on said base and extending substantially the full length of said base and a secondary lever fulcrumed intermediate its ends on said base and pivotally secured adjacent one end to said platform and adjacent the other end to an intermediate portion of said actuating lever, whereby said platform is elevated, and locking means for said actuating lever to hold said platform elevated.

2. An elevating mechanism, comprising a base and a movable platform, actuating means therefor, comprising an actuating

lever pivoted on said base and a plurality of secondary levers pivoted on said base and connected adjacent their inner ends to adjacent points on said actuating lever, said secondary levers being connected to separated points on said platform so as to elevate the same.

3. An elevating mechanism, comprising a base and a movable platform, actuating means therefor, comprising an actuating lever pivoted on said base, and a plurality of radially arranged secondary levers fulcrumed intermediate their ends on said base and connected adjacent their inner ends to adjacent points on said actuating lever, said secondary levers being connected adjacent their outer ends to said platform.

4. In an elevating truck, a base and a movable platform, actuating means therefor, comprising an actuating lever pivoted at one end on said base and a secondary lever formed of two flat bars spaced apart, means for connecting said lever to the base comprising a bar having a flat head pivotally supporting said secondary lever intermediate its ends, a flat link connecting one end of said secondary lever and an intermediate portion of said actuating lever, and a flat post supporting said platform and connected to the opposite end of said secondary lever, the flat bars of said secondary lever, extending on each side of each of said connecting means and being spaced thereby, and pivotally connected thereto by pins extending through alined perforations in said bars and connecting means.

5. In an elevating truck, a base and a movable platform, actuating means therefor, comprising an actuating lever pivoted on to said base, and a secondary lever pivotally secured adjacent one end to said platform and adjacent the other end, to said actuating lever, and an adjustable fulcrum member for said secondary lever, mounted on said base and comprising a threaded shank and a nut on said shank, said nut resting on said base and supporting the fulcrum member.

6. An elevating mechanism, comprising a

base and a movable platform, actuating means therefor, comprising an actuating lever pivoted on said base and a plurality of radially arranged secondary levers, a vertically adjustable fulcrum for each of said levers, each of said levers being connected adjacent its inner end to said actuating lever and connected to said platform so as to raise and lower the same.

7. An elevating mechanism, comprising a base and a movable platform, actuating means therefor, comprising an actuating lever pivoted on said base, and a plurality of radially arranged secondary levers, a vertically adjustable fulcrum for each of said levers, comprising a nut resting on said base and a bolt threaded in said nut and supported thereby.

8. An elevating mechanism, comprising a base and a movable platform, tension springs connecting said base and platform, actuating means therefor, comprising an actuating lever pivoted on said base and a plurality of secondary levers pivoted on said base and connected adjacent their inner ends to adjacent points on said actuating lever, said secondary levers being connected to said platform so as to elevate same, and locking means for said actuating lever.

9. In an elevating truck, a base and a movable platform, actuating means therefor comprising a centrally mounted actuating lever pivoted at one end adjacent one end of said base and normally extending beyond the other end of said base so as to serve as a foot pedal, and a plurality of secondary levers pivotally mounted on said base and connected near their inner ends to adjacent points on an intermediate portion of said actuating lever, and at distant points to spaced portions of said platform.

In testimony whereof I affix my signature in presence of two witnesses.

MILES E. BAILEY.
